UNITED STATES PATENT OFFICE.

IRVING C. JENNINGS, OF SOUTH NORWALK, CONNECTICUT, ASSIGNOR TO NASH ENGINEERING COMPANY, OF SOUTH NORWALK, CONNECTICUT, A CORPORATION OF CONNECTICUT.

PUMP.

Application filed July 2, 1921. Serial No. 482,179.

The present invention relates to pumping apparatus and particularly to liquid pumps having rotary pistons.

Heretofore rotary pumps have not been used generally to pump liquids in cases where the liquid to be pumped is at a lower level than the pump itself because of the difficulty in priming the pump upon starting to remove all air and gas from the intake, which when present in only small amounts prevents the successful operation of the pump. Where such pumps are located below the tank or receptacle containing the liquid to be pumped they are automatically primed by liquid which flows downwardly from the tank and into the intake of the pump. It is very frequently desired however to install a rotary pump above the tank or receptacle in which the liquid is held and in accordance with the present invention a pumping apparatus is provided in which a rotary piston pump is used to impel the liquid and an auxiliary means is provided for automatically priming the rotary liquid pump whenever it is called into operation, so that the pump may be placed above the tank or receptacle containing the liquid to be pumped and will operate efficiently and satisfactorily in such position. The priming device, which is preferably an air pump for exhausting the air or gas in the inlet conduit of the liquid pump, is also preferably connected to the driving means for the liquid pump so that whenever the last mentioned pump is called into operation it will be automatically primed and will operate promptly and without waste of power. Once in operation continuous action of the liquid pump is assured by the continuous operation of the primer which prevents any gathering of air in the intake to the pump.

One form of the invention is illustrated in the accompanying drawings but it will be understood that the invention may be embodied in various forms of which that illustrated is an example. In the drawings:

Fig. 1 illustrates diagrammatically the pumping apparatus; and
Fig. 2 is a longitudinal section through the rotary pump with its associated priming apparatus.

The numeral 10 indicates a tank or receptacle such as a sump or hot well and the

numeral 11 indicates a second tank into which the water pumped may be discharged. The conduit through which the water is pumped includes a pipe 12 having its lower end or intake protected by screen 13 and submerged in tank 10, and a pipe 14 the upper end of which opens into tank 11. The lower end of pipe 14 communicates with the exhaust port of a pump having a rotary piston 15, and the upper end of pipe 12 communicates with a separating chamber 16 which in turn is in communication with the intake of the pump.

Associated with the liquid pump just described is a gas pump which may be of any desired make or construction but is preferably of the well known hydro-turbine type, constructed in accordance with the inventions in gas pumps, described and illustrated in patents to L. H. Nash, Numbers 953,222 and 1,091,529 and to I. C. Jennings, 1,297,692, respectively. As shown clearly in Figure 2, this air pump has a rotary impeller or piston 18', which is mounted upon the same shaft 19 which supports piston 15 of the water pump, this shaft being driven by the electric motor 20 so that both gas and liquid pumps are simultaneously operated. The intake pipe 21 of the air pump communicates with the interior of the separating chamber 16 through a restricted orifice 22 which, while offering but slight resistance to the passage of air to the pump, offers a substantial resistance to the passage of liquid.

The outlet conduit from the air pump is indicated at 23 and this outlet opens into the top of a separating tank 24 from which the air escapes through a pipe 25, the tank retaining any water which may flow from the air pump. The bottom of the separating tank 24 communicates with the interior of the air pump by means of a pipe 26, and an overflow 27 leading back to the tank 10 serves to carry off any excess water which may happen to be drawn through the restricted orifice 22 and the pipe 21 into the air pump and thence to the separating tank 24. The water in the separating tank 24 normally stands with its level at the height of the upper end of overflow pipe 27, which level is higher than the point where pipe 26 enters the air pump, so that a priming charge normally tends to flow from the tank to this pump at all times.

The motor 20 is preferably started and stopped automatically, having a main line switch 30 adapted to be opened and closed by a circuit closing switch 31 which is in turn controlled by a float 32. Float 32 moves vertically on a rod 33 connected to switch arm 31' and stops 34 are secured to this rod, one stop being at the lower end of the rod near the bottom of the tank 10 and the second stop being near the top of the tank. As the tank fills, float 32 will strike the upper stop 34, close switch 31 and operate main line switch 30 to start the motor. The air pump exhausts the air from the separating chamber 16 so that water is lifted by suction through intake tube 12 and primes the inlet of the liquid pump. Water entering the inlet of this pump displaces the air contained therein and the pump is enabled thereby to exercise a lifting force on the column of water and to force it through pipe 14 and into the elevated tank 11 or to any other place to which it is to be pumped.

25 A non-return valve 35 in the pipe 14 prevents a back flow of liquid through the pump when the pump is not in operation and also prevents air from being drawn downwardly and through the pump into the separating chamber 16 when the pump is first started. As the tank 10 empties float 32 descends and finally contacts with the lower stop 34, opening switch 31 and stopping the motor. The apparatus will then be inactive until the tank again fills, when this cycle of operations will be repeated.

Having thus described the invention what is claimed as new and desired to be secured by Letters Patent is:

40 1. Pumping apparatus of the character described including in combination, a rotary liquid pump having a gas and liquid

separating chamber at its intake side, a rotary gas pump of the type employing liquid for its pumping action, a conduit connecting said chamber with the intake of the gas pump, constructed so that at all times a free passage for gas is provided, but little liquid can flow therethru, and means constantly supplying said gas pump with the liquid necessary for its operation. 50

2. Pumping apparatus of the character described including in combination, a rotary liquid pump having a gas and liquid separating chamber at its intake side, a rotary gas pump of the type employing liquid for its pumping action, a conduit connecting said chamber with the intake of the gas pump, said conduit having a restricted orifice, whereby at all times a free passage for gas is provided, but little liquid can flow through said orifice, a gas and liquid separating tank connected to the outlet of the gas pump, and an independent conduit extending from said tank to said gas pump to keep the latter supplied with the liquid necessary for its operation. 60

3. In a pumping apparatus in combination, a unitary structure comprising a rotary liquid pump and a hydro-turbine gas pump, said structure being adapted to be placed above the level of liquid to be pumped, a liquid and gas separating chamber on the intake side of the liquid pump, a connection between said chamber and the intake side of the gas pump whereby the gas pump is adapted to prime the liquid pump, a gas and liquid separating tank on the discharge side of the gas pump, said tank being adapted to supply the gas pump with 70 the liquid necessary for its operation. 75

In testimony whereof I hereunto affix my signature.

IRVING C. JENNINGS.
